UNITED STATES PATENT OFFICE.

LEO KRESSER, OF PASSAIC, NEW JERSEY.

UNLOADING-MACHINE.

1,170,826.

Specification of Letters Patent. Patented Feb. 8, 1916.

Application filed October 27, 1914. Serial No. 868,794.

To all whom it may concern:

Be it known that I, LEO KRESSER, a citizen of the United States, residing at Passaic, in the county of Passaic and State of New Jersey, have invented a new and useful Unloading-Machine, of which the following is a specification.

My invention relates to an improvement in removing material from bins and railroad cars with the object of eliminating manual labor usually required for trimming and feeding the material to the unloading machine.

With this object in view I suspend a bucket elevator from a frame and oscillate the elevator across the container in such a way that the tailshaft moves in an almost straight line and parallel to the bottom of the container. The machine can also be moved in a line parallel to the side of the container.

The invention is illustrated in the accompanying drawing.

Figure 1 is a plan of the machine. Fig. 2 is a front elevation and Fig. 3 is a side elevation.

The same reference characters denote like parts in each of the figures of the drawing.

A bucket elevator marked "E" has a head-shaft marked "a" and a tail-shaft marked "b" which shafts are provided with pulleys "d" and "f" respectively over which a pliable member is strung which carries the buckets marked "c". The shafts are supported in a frame "i". The head-shaft "a" also carries a pulley "k" which is driven by means of driving member "l" from shaft "n". The head-shaft is connected with this shaft "n" by means of two links "m" and "m'". Shaft "n" is supported by frame "o". The frame "i" of the elevator has two rollers "p" and "p'" attached by means of shaft "h". These rollers "p" and "p'" are running in curved tracks formed by the frame "o". Shaft "h" is connected with cranks "g" and "g'" by means of the connecting rods "r" and "r'". The cranks "g" and "g'" are part of the crankshaft "s". This crank-shaft carries a gear "t" which is in mesh with a gear "v" on shaft "u". Shaft "u" is supported in the trolley "T" and carries a pulley "w" by means of which power can be transmitted to shaft "u" from any source whatsoever; in the drawing an electric motor is indicated. A pulley "w" on the shaft "u" transmits power to shaft "n" by means of driving member "v".

The frame "o" is fulcrumed on shaft "u" and is carried besides by two ropes "x" and "x'" which run over the pulleys "y" and "y'" to drums "z" and "z'".

The trolley "T" is running on tracks "R" and "R'". The rope "N" is fastened to the trolley "T" with both of its ends and is running over the pulleys "K" and "K'".

A chute "C" is arranged to receive the material from the elevator.

The operation of the machine is as follows: The elevator buckets pick up the material in the container, raise it and discharge it into the chute "C". The lower part of the elevator is moved across the container in a straight line and by this motion sweeps the whole width of the container. As soon as a cross motion is finished the trolley is moved parallel to the side of the container. The operation of unloading is started at one end of the container and by the intermittent motions of the trolley gradually the whole container is swept and unloaded. After the operation of unloading is finished the machine is hoisted up and removed from the container.

The elements of which the machine is composed and which are shown and described can be substituted by such modifications as the various arts would find to be suitable in special applications.

What I claim as my invention is the following:

1. In an unloading machine a movable frame and a bucket-elevator mounted therein in combination with a supporting structure which is provided with means for guiding the frame in two places lengthwise remote from one another for movement in two distinct directions, attachments to the frame to engage with the guiding means of the structure and means for oscillating the frame and driving the elevator.

2. In an unloading machine a movable frame and a bucket-elevator mounted therein in combination with a supporting structure which is provided with means for guiding the frame in two places lengthwise remote from one another for movement in two distinct directions, attachments to the frame to engage with the guiding means of the structure, pushrods attached to said frame, a crank mechanism acting upon the pushrods and driving machinery for the crank mechanism and the elevator.

3. In an unloading machine a pivoted

structure provided with curved tracks serving as a support in combination with a movable frame and a bucket elevator mounted therein, links connecting the headshaft of 5 the elevator with the structure, rollers attached to the frame and running on the curved tracks of the structure, pushrods connected with and acting upon the frame of the elevator, cranks, a crankshaft and 10 driving machinery actuating the pushrods and driving the elevator, means for hoisting the free end of the structure.

4. In an unloading machine a pivoted structure provided with curved tracks serving as a support in combination with a movable frame and a bucket elevator mounted 15 therein, links connecting the headshaft of

the elevator with the structure, rollers attached to the frame and running on the curved tracks of the structure, pushrods 2 connected with and acting upon the frame of the elevator, cranks, a crankshaft and driving machinery actuating the pushrods and driving the elevator, a trolley to carry the structure and means for hoisting the 2 free end of the structure, tracks to carry the trolley and means of propulsion of the trolley.

In witness whereof I have hereunto set my hand in the presence of two witnesses. 3

LEO KRESSER.
